UNITED STATES PATENT OFFICE

FRANK HENNEBÖHLE, OF CHICAGO, ILLINOIS

OIL BURNER

Application filed August 26, 1926. Serial No. 131,709.

The invention generally relates to oil burners of the type disclosed in my Patent No. 1,555,855 issued October 6, 1925, and primarily has for its object to provide certain new and useful improvements in the burner disclosed in the patent referred to whereby a more even and efficient distribution of the oil film, a more perfect combustion and a more efficient flame distribution is provided for than is possible in the patented structure referred to or in the disclosures of the prior art.

In its more detailed nature the invention seeks to improve the burner disclosed in Patent No. 1,555,855 by providing an oil feed tube adapted to lie in the uppermost oil groove and having fine orifices through which oil is delivered into the said groove to assure more even distribution of the oil film, an annular heated air passageway for effecting a more efficient preheating of the oil in the oil grooves and to overcome tendency of the incoming air to chill said oil grooves, and a spreader ring for more efficiently spreading the flame produced by combustion.

With the above and other objects in view that will hereinafter appear the invention further resides in the novel details of construction, combination and arrangement of parts, all of which will be first fully described, then be particularly pointed out in the appended claims, reference being had to the accompanying drawing in which:—

Figure 1 is a central vertical cross section illustrating the invention.

Figure 2 is a plan view, the spreader ring being removed.

Figure 3 is an inverted perspective view of the oil feed tube.

In the drawing in which like numerals of reference indicate like parts in all of the figures, 1 represents the base portion of the burner which is provided with an upright peripheral flange 2. The burner may be hook bolted as at 3 to the particular grate structure 4 upon which it is to be mounted. The base 1 is provided with a depending flange 5 which is adapted to engage the grate so as to provide an air space above the grate surrounded by said flange. When the burner

is secured on the grate the space surrounding it is covered with fire clay to assure induction of draft upwardly through the burner only as described and shown in my Patent No. 1,555,855.

A frusto-coniform throat 6 extends upwardly from the base 1 and merges with a cylindrical neck 7 which extends up into, but terminates short of, the top of the crown cap 8, removably supported upon the neck 7 by the mounting ring 9 spaced from the said cap by the webs 10.

In my present invention the outer face of the frusto-coniform throat 6 is smooth and a frusto-coniform sleeve 11 is fitted over it and held in spaced relation by the ribs 12 which engage the outer surface of the said throat. Thus a well defined annular air passage 13 is provided between the outer surface of the throat 6 and the sleeve, the purpose for which will be described later.

The crown cap 8 is curved downwardly to surround the upper edge of the sleeve 11 and provide an annular restricted discharge throatway 14 adapted to discharge onto the outer surface of the said sleeve.

Thus the draft air passing up through the grate 4 will pass through the throatway 6 and neck 7 and be directed against the top of the crown cap 8 and deflected downwardly through the restricted discharge throatway 14 against the outer surface of the sleeve 11.

The outer surface of the sleeve 11 is provided with a plurality of stepped or terraced annular oil grooves 15, the lowermost one of which discharges into an overflow groove 16 in event of failure of combustion. A drain 17 communicates with the groove 16 and as the purpose of this drain is fully disclosed in my patent hereinbefore referred to, further description here is deemed unnecessary.

A ring-like fuel oil distributing tube 18 is loosely laid into the uppermost oil groove 15 and has its extremities bent downwardly at right angles as at 19 and projected into receiving pockets 20 formed in the sleeve 11 and communicating with the fuel delivery duct 21. Fuel oil is supplied to the duct 21 by the fuel delivery pipe 22 which is screwed into the boss 23 with which the sleeve 11

is provided. The tube 18 is provided with a plurality of fuel distributing orifices 24 directed downwardly into the uppermost oil groove 15.

5 The frusto-coniform throat 6 is provided with a suitable cut-out portion 25 to accommodate the boss 23 of the sleeve 11.

10 The ends of the angle portions 19 may be upset slightly as at 26 if desired to prevent inadvertent removal of the tube 18.

15 In operation, fuel oil is evenly distributed in the uppermost oil groove 15 through the orifices of the tube 18 and this groove, overflowing, provides and assures the flow of a uniform thin film of oil down the grooved outer surface of the sleeve 11. By providing the distributing tube 18 a more uniform film of fuel oil is provided and more efficient combustion is assured than is possible in my 20 patented structure referred to. As the crown cap 8 becomes highly heated the draft air directed against the top thereof will be pre-heated and so directed against the thin film of oil as to effectively act to vaporize the 25 same and greatly aid in providing for efficient combustion.

The crown cap 8 is provided with an annular flange 27 for supporting the deflecting ring 28 which serves to spread and deflect 30 the flame outwardly over a greater area than it would cover under ordinary circumstances.

35 By providing the annular air passage 13 between the throat 6 and sleeve 11, means is provided for shielding the said sleeve against any cooling tendency occasioned by passage of draft air up through the said throat 6. Heated air is directed into that passage 13 from the crown cap and serves not only to 40 insulate the sleeve 11 from the relatively cool air-contacted throat 6, but also to heat the said sleeve and further contribute to the ready vaporization of the oil film and more perfect combustion.

45 From the foregoing description, taken in connection with the accompanying drawing, it is thought that the novel details of construction, the manner of use and the advantages of the invention will be readily apparent to those skilled in the art to which it relates.

What I claim is:

1. A device of the class described comprising a base, a frusto-coniform throat extending upwardly from the base, a neck extending upwardly from the throat and forming a restricted air duct, a heating and expanding crown cap surrounding the neck and into which the neck discharges and which has 55 the edge thereof extended to surround the neck and form a restricted annular discharge passage discharging onto the outer surface of the said throat, a frusto-coniform sleeve surrounding said throat in spaced relation and in position for having the discharge pas-

sage discharge onto the outer surface thereof and into the space between said throat and sleeve, and means for distributing a film of fuel oil onto the outer surface of said sleeve.

2. A device of the class described comprising a base, a frusto-coniform throat extending upwardly from the base, a neck extending upwardly from the throat and forming a restricted air duct, a heating and expanding crown cap surrounding the neck and into which the neck discharges and which has the edge thereof extended to surround the neck and form a restricted annular discharge passage discharging onto the outer surface of the said throat, a frusto-coniform sleeve surrounding said throat in spaced relation and in position for having the discharge passage discharge onto the outer surface thereof and into the space between said throat and sleeve, said sleeve having a plurality of annular stepped oil grooves, an oil distributor tube mounted in the uppermost oil groove and provided with a plurality of distributor orifices directed into said groove, and means for supplying fuel oil to said tube.

3. A device of the class described comprising a base, a frusto-coniform throat extending upwardly from the base, and having a series of relatively shallow annularly stepped oil grooves in the outer surface thereof, a neck extending upwardly from the throat and forming a restricted duct, a cap supported by the neck and into which the neck discharges and having its top spaced above but in close relation to said neck and the edge thereof positioned to provide a restricted annular air discharge throat-way surrounding the outer surface of the frusto-coniform throat, and an oil distributor tube mounted in the uppermost oil groove and provided with a plurality of equi-distantly spaced distributor orifices directed downwardly into the said uppermost groove, and means to direct fuel oil upwardly into the tube.

4. A device of the class described comprising a base, a frusto-coniform throat extending upwardly from the base, a neck extending upwardly from the throat and forming a restricted air duct, a heating and expanding crown cap surrounding the neck and into which the neck discharges and which has the edge thereof extended to surround the neck and form a restricted annular discharge passage discharging onto the outer surface of the said throat, a frusto-coniform sleeve surrounding said throat in spaced relation and in position for having the discharge passage discharge onto the outer surface thereof and into the space between said throat and sleeve, means for distributing a film of fuel oil onto the outer surface, said crown cap having a mounting ring loosely fitting the upwardly extended neck, and

webs supporting the mounting ring in the crown cap, said webs being adapted to rest upon the frusto-coniform sleeve to support said crown cap.

5. In a device of the class described, a base, a frusto-coniform throat extending upwardly from the base and having a neck extending upwardly from said throat to form a restricted air duct, a crown cap having a top 10 and a constricted throat and means to support said cap on said neck, said cap having a narrow annular flange surrounding the body below the level of the top thereof, and a spreader ring removably fitted over said 15 cap and resting on said flange, substantially as described.

6. In a device of the class described, a base, a frusto-coniform throat extending upwardly from the base, and a cap over the 20 throat having a discharge passage; a frusto-coniform sleeve surrounding said throat in spaced relation and in position for having the discharge passage discharge onto the outer surface thereof and into the space between said throat and sleeve, said sleeve having a plurality of annular stepped oil 25 grooves, an oil distributor tube mounted in the uppermost oil groove and provided with a plurality of distributor orifices directed 30 into said groove, means for supplying fuel oil to said tube, said fuel oil supplying means including a delivery pipe extending upwardly through the frusto-coniform throat, said throat having fuel oil distributing 35 and tube end receiving pockets in communication with the delivery pipe, and said tube having its ends adjacent and bent angularly and inserted in the receiving pockets to receive fuel oil and secured against inadvertent removal.

7. In a burner of the class described, a base, a neck extending upwardly from the base to constitute an air passageway, means for supplying fuel oil to said base around 45 said neck, a sleeve surrounding said neck, means to hold said sleeve in spaced relation to said neck, and means for heating the air passing out of said passageway and delivering the heated air over the outer surface 50 of said sleeve and into the top of the space between said sleeve and neck whereby a portion of the heated air will pass downwardly into said space for the purposes specified.

8. In a burner of the class described, a 55 base, a neck extending upwardly from the base to constitute an air passageway, means for supplying fuel oil to said base around said neck, a sleeve surrounding said neck, means to hold said sleeve spaced from said 60 neck to provide an air passageway between the neck and sleeve, a cap supported over said neck and having air baffling surfaces for directing the air passing into the cap from said first mentioned passageway over 65 the outer surface of said sleeve and into the

top of the air passageway which is located between said sleeve and said neck, said cap being located in the flame zone of the burner to become heated and thereby heat the air before delivering it over the outer surface of 70 said sleeve and into said passageway between said sleeve and said neck.
